UNITED STATES PATENT OFFICE.

WILLIAM L. DUDLEY, OF NASHVILLE, TENNESSEE.

SPARK-ARRESTER.

No. 831,656.

Specification of Letters Patent.

Patented Sept. 25, 1906.

Application filed January 6, 1906. Serial No. 294,882.

To all whom it may concern:

Be it known that I, WILLIAM L. DUDLEY, a citizen of the United States, residing at Nashville, in the county of Davidson and State of Tennessee, have invented certain new and useful Improvements in Spark-Arresters; and I do hereby declare the following to be a full, clear, and exact description of the invention, such as will enable others skilled in the art to which it appertains to make and use the same.

My invention relates to that class of devices commonly termed "spark-arresters" which have for their object the elimination of sparks and cinders from the gaseous products of combustion. These devices are more usually employed wherever engines are operated under forced draft, as in such cases solid particles of considerable size and weight are easily carried out of the stack with the gases. In locomotives the sparks and cinders emitted by the stack are frequently the cause of fires along the right of way and are a source of annoyance to passengers.

The object of the present invention is to provide a simple and efficient means for eliminating sparks and cinders from the gaseous products of combustion prior to their escape from the stack without decreasing the draft and without creating back pressure upon the cylinders.

To this end my invention, generally stated, embraces means for causing the gaseous products of combustion to flow or move in a curved path, whereby the solid particles carried by said gases are projected tangentially by centrifugal force and thus eliminated prior to the mixture of the exhaust-steam with said gases. The particular means shown in the drawings for accomplishing the desired result is embodied in a horizontally-disposed curved peripherally-perforated smoke-flue interposed between the boiler-tubes and the stack and in such relation to the exhaust-nozzle as that the steam from the latter induces the flow of the gases in the curved smoke-flue and mixes with said gases after the elimination of cinders therefrom, whereby a free draft is maintained and back pressure upon the cylinders is avoided.

There are other minor features of invention involved in the construction and relative arrangement of the parts, all as will hereinafter more fully appear.

In the drawings accompanying this speci-

fication and forming part of the same, Figure 1 is a longitudinal central vertical section on the line 1 1, Fig. 3, of a spark-arrester embodying my invention. Fig. 2 is a transverse vertical section thereof on the line 2 2, 60 Fig. 3. Fig. 3 is a horizontal section of the same on the line 3 3, Fig. 1. Fig. 4 is a view similar to Fig. 3, but showing a modification wherein a series of slats are substituted for the perforated outer wall of the curved flue. 65 Fig. 5 is a longitudinal central vertical section on the line 5 5, Fig. 6, of a modified form of the device, showing the use of a single curved smoke-flue. Fig. 6 is a horizontal section on the line 6 6, Fig. 5, of the modified 70 form shown in Fig. 5; and Fig. 7 is a vertical section of a portion of the device taken on the line 7 7, Fig. 6.

Like symbols refer to like parts wherever they occur.

I will now proceed to describe my invention more fully, so that others skilled in the art to which it appertains may apply the same.

In the drawings, A indicates the front flue-sheet of a locomotive-boiler; B, that portion of the shell termed the "smoke-box," C, the stack; D D, the live-steam pipes leading from the dome to the cylinders and from which, if desired, a jet may be taken to the 80 exhaust-nozzle; E, the petticoat-pipe, and F the exhaust-nozzle, all or any of which parts may be of the usual or any approved construction, though by preference the vertical cross-section of the smoke-box transversely 90 of the boiler is of D form, for reasons which will hereinafter appear.

1 indicates the top, 2 the bottom, 3 the inner wall, and 4 the outer or peripheral wall of a smoke-flue of curved form embodying 95 my invention, the curvature being preferably an arc of about one hundred and eighty degrees, though a greater or lesser curvature may be given the flue, if desired. This smoke-flue, which may be of sheet metal, preferably sheet- 100 steel, abuts or is attached at its inner or inlet end to the front flue-sheet A of the boiler, surrounds and includes the rectilinear exhaust-nozzle F at its outlet, and is connected with or opens into or opens immediately below the 105 lower end of the petticoat-pipe E or the stack when the petticoat-pipe is omitted, so that the products of combustion after leaving the boiler-tubes are caused to take a curved path by the action of the exhaust- 110

steam, with which, however, said products do not unite or mingle until they reach a point where substantially all the heavier matters, such as sparks and cinders, have 5 been eliminated and only the gases and lighter products of combustion remain. The outer or peripheral wall of said curved smoke-flue is perforated, as at 4^a, to permit the escape of the sparks and cinders, and the lips or margins of said openings are preferably curved inwardly, as at 4^b, to intercept the sparks and cinders and direct them into the openings 4^a. In the construction shown in the principal figures of the drawings two 15 of said flues, each occupying a lateral half of the smoke-box B and each delivering at the center of the box below the petticoat pipe or stack, are shown, and the said flues have outer walls 6, which, in connection with trans- 20 verse walls 6^a, form a series of peripherally-disposed compartments 7, that communicate with the flue and open below into a dead-space b, beneath which is a hopper 8, provided with a slide-valve 9. This valve may 25 be operated from time to time by the engineer through the medium of a piston and cylinder connected with the air system of the engine to discharge the cinders at such times as the throttle is closed. If desired, how- 30 ever, a single curved smoke-flue of the character hereinbefore set forth may be employed and may be substantially centered with the rectilinear exhaust-nozzle F and the stack, as shown in Figs. 5 and 6 of the draw- 35 ings. In such case a short perforated deflecting cross-wall 10, delivering below into the dead-space, will be introduced to guide the products of combustion from said side of the boiler-tubes toward and into the inlet of 40 the curved smoke-flue.

In some instances, for the sake of simplicity of construction, instead of forming the peripheral wall with compartments 7, as shown in Fig. 3 of the drawings, said wall 45 may be formed of a series of slats 4^c, Fig. 4, between which the sparks and cinders will escape directly into the chamber B and drop thence into the dead-space or hopper beneath, and in order to prevent clogging said slats, if 50 desired, may be pivoted and connected to a rod in front of or outside the flue and may be operated by said rod, as in the case of a Venetian blind or a shaking-grate, to dislodge any obstructions.

55 As hereinbefore pointed out, the vertical cross-section of the smoke-box B transversely of the boiler is shown in Fig. 2 as of D form, while in the modification shown in Fig. 5 the cross-section of the smoke-box 60 transversely of the boiler is circular or of the common form, and it will be noted that in the case of the D cross-section, Figs. 1 and 2, the curved smoke-flue may be narrowed and deepened, as a result of which any lift from 65 the lower tubes of the boiler is avoided and

the deposit and elimination of cinders is facilitated.

A spark-arrester embodying the principles of construction hereinbefore set forth will operate as follows: Induced by the exhaust steam issuing from the nozzle the travel of the products of combustion from the boiler-tubes to the stack will be in a curved path substantially encircling the exhaust-column, and the centrifugal force of the moving 75 gases acting on the sparks and cinders will project the latter tangentially through the openings in the peripheral wall of the smoke-flue and into the dead-space beyond, the products of combustion entering the path of 80 the exhaust-steam after being relieved of such matters as would be objectionable if emitted from the stack.

Among the advantages incident to my invention hereinbefore set forth are, first, the avoidance of any obstruction to the draft, such as results when spark-arresting devices are interposed between the exhaust-nozzle and the stack; second, the avoidance of back pressure on the cylinders in general and of 90 back pressure of one cylinder upon the other, and, third, the prevention of cross-firing of the exhaust-steam in the stack, all of which adds to the efficiency of the engine and saves fuel.

Having thus described my invention, what I claim, and desire to secure by Letters Patent, is—

1. In a spark-arrester, the combination of a flue-sheet, a smoke-box, a stack, an exhaust-nozzle within the smoke-box in vertical alinement with the stack, and an arc-shaped smoke-flue horizontally disposed within the smoke-box, said flue having an inlet adjacent to the flue-sheet and an outlet 105 in vertical alinement with the stack and which incloses the exhaust-nozzle.

2. In a spark-arrester, the combination of a flue-sheet, a smoke-box, a stack, an exhaust-nozzle within the smoke-box in alinement with the stack, and an arc-shaped smoke-flue having its outer wall perforated at intervals, said smoke-flue horizontally disposed within the smoke-box and having an inlet adjacent to the flue-sheet and an outlet 115 adjacent to the exhaust-nozzle and beneath the stack.

3. In a spark-arrester the combination of a flue-sheet, smoke-box, stack, an exhaust-nozzle located within the smoke-box beneath the stack, and a plurality of arc-shaped smoke-flues horizontally disposed within the smoke-box, each of said flues having an inlet adjacent to the flue-sheet and an outlet adjacent to the exhaust-nozzle and beneath the 120 stack.

4. In a spark-arrester, the combination of a flue-sheet, a smoke-box, a stack, an exhaust-nozzle within the smoke-box in vertical alinement with the stack, and a plurality 130

of arc-shaped smoke-flues horizontally disposed within the smoke-box, said smoke-flues having a common inlet adjacent to the flue-sheet, and a common outlet beneath the stack and which incloses the exhaust-nozzle.

5. In a spark-arrester, the combination of a flue-sheet, a smoke-box, a stack, an exhaust-nozzle within the smoke-box in vertical alinement with the stack, and a plurality of horizontally-disposed arc-shaped smoke-flues located on opposite sides of the smoke-box, each of said flues having an inlet adjacent to the flue-sheet and an outlet which incloses the exhaust-nozzle and is in vertical alinement with the stack.

10. In a spark-arrester, the combination of a smoke-box, a stack, an exhaust-nozzle within the box in vertical alinement with the stack, and a curved smoke-flue having an inlet, an outlet, and a perforate peripheral wall, said smoke-flue being horizontally-disposed within the smoke-box and having its outlet beneath the stack and surrounding the exhaust-nozzle.

15. In a spark-arrester, the combination of a smoke-box, a stack into which the smoke-box opens, an exhaust-nozzle alined with and delivering into the stack, a curved smoke-flue having a perforated peripheral wall, said smoke-flue disposed within the smoke-box and having an outlet which in-

closes the exhaust-nozzle and is in vertical alinement with the stack.

8. In a spark-arrester, the combination of a smoke-box, a stack into which the smoke-box opens, an exhaust-nozzle within the smoke-box, and an arc-shaped smoke-flue horizontally disposed within the smoke-box and having an outlet which incloses the exhaust-nozzle.

35. In a spark-arrester, the combination of a smoke-box, a stack into which the smoke-box opens, an exhaust-nozzle within the smoke-box, and an arc-shaped smoke-flue having its peripheral wall perforated at intervals throughout its course, said smoke-flue being disposed within the smoke-box and having an outlet adjacent to the exhaust-nozzle.

40. In a spark-arrester, the combination of a smoke-box of D-shaped cross-section, a stack into which the smoke-box opens, an exhaust-nozzle, and an arc-shaped smoke-flue horizontally disposed within the smoke-box.

45. In testimony whereof I affix my signature in presence of two subscribing witnesses.
